UNITED STATES PATENT OFFICE.

PERCY WALTER DRUITT AND WILLIAM ROBERT GILPIN, OF LONDON, ENGLAND.

SPACE-CASTING MECHANISM OF TYPOGRAPHIC MACHINES.

1,407,460.

Specification of Letters Patent. Patented Feb. 21, 1922.

Application filed October 12, 1920. Serial No. 416,530.

To all whom it may concern:

Be it known that we, PERCY WALTER DRUITT and WILLIAM ROBERT GILPIN, both subjects of the King of Great Britain, and 5 residing in London, England, have jointly invented certain new and useful Improvements in Space-Casting Mechanisms of Typographic Machines, of which the following is a specification.

10 When type is set up in the printing form with spaces of the same length as the type less the depth of strike, a very slight longitudinal displacement of the spaces renders them liable to receive ink and to make an 15 impression on the paper and it has been proposed to obviate this by reducing the length of such spaces subsequent to the casting operation or by casting the spaces shorter than the type by means of a differential body 20 slide in the type mould.

The latter plan, which has been used in mechanically controlled automatic type casting machines, is applied according to the present invention to typographic machines 25 of the kind in which the matrices are assembled in line by means of keyboard mechanism and then pass successively to the casting mechanism, by making the bottom of the set notch in the edge of the matrix stepped, 30 the shallower step serving to determine the correct set width, while the deeper step enables a differential mould blade to cut off the front part of the mould aperture.

The invention will be more specifically described with reference to the accompanying drawings, wherein

Fig. 1 is a front elevation of the mould and movable blade slides;

Fig. 2 is a plan view of same with top 40 mould block removed; and

Fig. 3 is a perspective detail showing the front portion of the mould blades.

The two movable parts *a*, *b* of the mould blade which are moved forward to close the 45 mould *c* by means of spring urged slides *e*, *f* capable of independent forward movement are each provided with a projecting lug *a*¹, *b*¹ respectively adjacent to their casting ends, these lugs being arranged vertically 50 one over the other and adapted to engage the set notch of the matrix *d* when the latter

is clamped on the mould substantially as described in British Patent Specification No. 1903 of 1900. In the case of a character or a type-high space the bottom of the set notch of the matrix is in one plane and the casting ends *a*⁰, *b*⁰ (Fig. 3) of the blades are in alignment at the moment of casting, the metal being injected into the mould against the face of the matrix.

If, however, a low space is required, the set notch of the matrix is stepped, as shown at *d*¹, *d*², the shallower step *d*¹ against which the lug *a*¹ on the main part *a* of the mould blade abuts serving to determine the correct 65 set width, while the deeper step *d*² permits the auxiliary blade *b* to move forward so as to cut off the front part of the mould aperture. In this case the metal is injected against the auxiliary blade and a shortened 70 casting produced.

Having thus described the nature of the said invention and the best means we know of carrying the same into practical effect, we claim:—

1. In typographic machines wherein the matrices are assembled in line by means of keyboard mechanism and then pass successively to the casting mechanism, space casting mechanism comprising a space matrix 80 having a stepped set notch therein, and a mould blade in two parts relatively movable to each other and cooperating with the respective steps of the set notch, one step serving to determine the correct set width, while 85 the other step determines the height or length of the cast space.

2. In space casting mechanism as claimed in Claim 1, a mould blade in two parts capable of independent movement and having projecting lugs adjacent to their casting ends arranged vertically one over the other and a space matrix having a stepped set notch with which the said projecting lugs and the differential movable blade are adapted to engage when the matrix is clamped in the mould.

In testimony whereof we have signed our names to this specification.

PERCY WALTER DRUITT.
WILLIAM ROBERT GILPIN.
